PAUL W. KERR AND ARTHUR E. JONES, OF ELKHART, INDIANA, ASSIGNORS TO HENRY WEIS MANUFACTURING COMPANY, INC., OF ELKHART, INDIANA, A CORPORATION OF INDIANA

SHOWER BATH CONSTRUCTION

Application filed November 16, 1931. Serial No. 575,294.

This invention relates to shower bath constructions, and among other objects aims to provide an improved shower cabinet receptor and to facilitate its manufacture.

5 The invention may be readily understood by reference to one construction embodying the invention and disclosed in the accompanying drawing.

In said drawing:

10 Fig. 1 is a plan view of a shower receptor. Fig. 2 is a transverse section on the plane 2—2 of Fig. 1, showing the receptor and the lower portion of a superposed shower cabinet.

15 Fig. 3 is a section similar to that of Fig. 2 but showing only one side of the receptor on an enlarged scale.

Fig. 4 is a section similar to Fig. 3 but taken on the plane 4—4 of Fig. 1 at the entrance opening to the shower cabinet.

20 Shower cabinets which are assembled at the point of installation upon a receptor, require not only a receptor which is accurately made to the dimensions of the cabinet but one which is capable of being joined to the latter 25 in a leak proof joint. If the receptor is made at the point of installation or cast in situ—which can be done to advantage—is must be formed to accurate size, particularly if it is to have a pre-manufactured cabinet such as a 30 sheet metal cabinet, erected upon and joined to it. Receptors of this character may advantageously be made from a decorative cementitious material such as terrazzo, with or without additional pigments.

35 In the illustrative shower construction the walls 10 of the cabinet, which in this case are sheet metal, are joined to the receptor 11 by a base flange 12 having an angularly disposed locking extremity 13 which seats in a groove 40 14 in the receptor. The dimensions of the base flange, the extremity 13, and its relation to the base flange being fixed, the receptor rim 15 must be shaped to exactly corresponding dimensions in order to secure a proper fit and 45 a tight leak proof joint.

The foregoing receptor dimensions are in the present case determined by a preformed rim 16, in this case of metal, which is shaped to conform exactly to the aforesaid cabinet dimensions and which serves as a mold section for casting the receptor. As here shown, the aforesaid rim comprises a ledge 17 which is shown inclined to the vertical at an angle corresponding to the inclination of base flange 12 of the cabinet and which in this case forms the entire upper surface of the receptor sides. The rim structure also includes a section 18 which forms the groove 14 and which in this case is integrally connected with the ledge by connecting section 19 forming the inner face of the upper portion of the receptor sides. The lower edge of the rim is anchored in the plastic material forming the receptor by a return flange 20 which extends inwardly from the extremity of the lower face section 21 of the rim. The rim is advantageously made up exactly to the dimensions of the cabinet enclosure which in this case is square or rectangular in shape, and when used as a part of the receptor mold structure it insures the proper dimensioning of the rim or curb of the receptor.

50 The cabinet side walls 10 in this case terminate at spaced points 22 and 23 along one side of the receptor to provide an entrance opening 24 into the shower cabinet. The ends of the flanges 13 of the shower cabinet engage abutments at the points 22 and 23 to prevent their inward movement so as to hold the base flanges of the cabinet properly positioned on the receptor sides and in the groove 55 14. These abutments in the present case are provided by a metal channel shaped section 25 similar in character to the rim 16 and conforming thereto in shape with the exception that it is not provided with portions 18 for forming the groove 14. The section 25 thus embodies a portion 26 extending across the end of the groove 14, providing strong abutments (at each end of the member 25, i. e. at 60 65 70 75 80 85 90 95

- the points 22 and 23) for the ends of flanges 13 for the purposes aforesaid. Moreover the cementitious material from which the receptor is made is not subjected to the cutting action of the edges of the metal flanges 13. The section 25 may be appropriately connected to the rim member 16 by welding, thus forming an integral rectangular form for determining the fixed dimensions of the receptor.
- 10 The dimensions of the receptor such as those of the exterior face of the sides as well as the receptor bottom and its thickness, may advantageously be determined by the location in which the receptor is to be placed.
- 15 Obviously the receptor may be either cast in situ or precast in a proper mold and moved into position. In either case the work may be done by the ordinary workman having no connection with the manufacture of the cabinets themselves and without knowledge of the character or dimensions of the cabinet, who will nevertheless produce an accurately dimensioned receptor by the use of the aforesaid rim structure. A series of receptors may be cast in situ by the use of a series of properly abutted rims which in such case may form the top surfaces of the sides of the combined receptors.
- 20 The rim structures are advantageously galvanized or provided with some other rust proof coating, or they may be made of a rust proof material.
- 25 Obviously the invention is not limited to the details of the illustrative construction since these may be variously modified. Moreover it is not indispensable that all features of the invention be used jointly since various features may be used to advantage in different combinations and sub-combinations.
- 30 Having described our invention, we claim:
- 35 1. In a shower bath construction the combination comprising a preformed shower cabinet, side walls having base flanges, a cementitious cast receptor having sides for receiving the cabinet side walls, and a fabricated receptor rim accurately conforming to the cabinet base flanges and cast into said receptor sides to provide accurately formed faces for receiving said flanges.
  - 40 2. In a shower bath construction the combination comprising a preformed shower cabinet, side walls having inwardly extending base and re-entrant locking flanges, a cementitious cast receptor having sides for receiving the cabinet side walls, and a fabricated receptor rim accurately conforming to said base flange and having a groove for receiving said re-entrant flange, and cast into said receptor sides to provide accurately formed faces for receiving said flanges.
  - 45 3. In a shower bath construction the combination comprising a preformed shower cabinet, side walls having inwardly extending base and re-entrant locking flanges, said

side walls terminating at spaced points to provide an entrance opening into the shower cabinet, and a fabricated metal rim conforming accurately to said base flanges and said cabinet dimensions and having a groove for receiving said re-entrant flange, said rim having abutments across said groove at the terminal points of said cabinet walls and flanges for holding the latter in position, said rim being cast into and forming a mold for a portion of the receptor side walls to provide accurately dimensioned surfaces for receiving the cabinet walls.

4. In a shower cabinet construction, a metal rim conforming to the exact dimensions of the cabinet and shaped to provide surfaces on which to seat the cabinet side walls, said rim being adapted to be cast into a shower receptor and to form a mold for a portion of said receptor.

5. A rim for cast shower cabinet receptors comprising in combination a channel member bent into rectangular shape conforming to the dimensions of a shower cabinet, with the flanges of said channel directed outwardly, the upper flange being of a width to provide a seat on the top of the receptor to receive shower cabinet side walls, the web of said channel being formed with a groove to receive portions of the cabinet side walls.

6. A rim for cast shower cabinet receptors comprising in combination a channel member bent into rectangular shape conforming to the dimensions of a shower cabinet, with the flanges of said channel directed outwardly, the upper flange being of a width to provide a seat on top of the receptor to receive shower cabinet side walls, the web of said channel extending downwardly and adapted to face the upper portion of the receptor sides, and the lower flange of said channel being arranged to be anchored in the receptor sides.

7. A rim for cast shower cabinet receptors comprising in combination a channel member bent into rectangular shape conforming to the dimensions of a shower cabinet, with the flanges of said channel directed outwardly, the upper flange being of a width to provide a seat on top of the receptor to receive shower cabinet side walls, the web of said channel extending downwardly and adapted to face the upper portion of the receptor sides, and the lower flange of said channel being arranged to be anchored in the receptor sides, said rim having abutments at each side of the cabinet door opening against which the lower edges of said cabinet may abut.

8. In a shower bath construction the combination comprising a ready made sheet metal shower cabinet having outwardly extending base flanges with downwardly extending extremity, a cast receptor having sides to support said cabinet, and a fabricated metal receptor rim cast into the upper portion of said receptor sides, said rim having

an upper flange resting upon the top of said receptor sides upon which said base flange seats and a downwardly extending flange facing the inside of said receptor sides and being anchored to said receptor sides, said upper flange and downwardly extending flange being preformed accurately to the cabinet base flange and its extremity.

In witness of the foregoing we affix our
10 signatures.

PAUL W. KERR.
ARTHUR E. JONES.
